UNITED STATES PATENT OFFICE.

ALEXANDER WINTON, OF CLEVELAND, OHIO.

FUEL-SUPPLY SYSTEM FOR AUTOMOBILES.

1,095,763.

Specification of Letters Patent.

Patented May 5, 1914.

Original application filed November 10, 1904, Serial No. 232,167. Divided and this application filed June 3, 1907. Serial No. 377,032.

To all whom it may concern:

Be it known that I, ALEXANDER WINTON, a citizen of the United States, residing at Cleveland, in the county of Cuyahoga and State of Ohio, have invented certain new and useful Improvements in Fuel-Supply Systems for Automobiles, of which the following is a specification, reference being had therein to the accompanying drawing.

10 This invention relates to improvements in fuel supply systems for automobiles, and is a division of my application filed November 10th, 1904, Ser. No. 232,167.

The object of this invention is to provide 15 a system of supplying the gasoline or fuel to the point where it is mixed with air, and which involves a main supply vessel which is located in a plane below the point where it is mixed with the air, and to lift this gasoline from the main or low down tank to an intermediate tank located in a plane above the point where the gasoline finally passes out and is mixed with the air, and to provide 20 automatic means for maintaining a uniform head or supply of gasoline irrespective of the amount of gasoline in the main or supply low-down tank or vessel, and to further provide an automatic means for maintaining 25 a level or head of gasoline between the said high-up tank or vessel and the gasoline outlet, which also automatically prevents the gasoline from flowing from the high-up tank when the engine is at rest.

In the accompanying drawings, Figure 1, 30 is a side view showing the relative levels of the parts embodying the present invention. Fig. 2, is an enlarged cross-sectional view on the line 2—2 of Fig. 1. Fig. 3 is a side view of the invention, showing it in position 40 on an automobile.

In carrying out my invention, a large main or supply reservoir or tank 1 is provided, and is located in a plane below the plane in which the carbureter 2 is located 45 and an auxiliary gasoline tank or chamber 3 is located in a plane above the carbureter. As here shown, the auxiliary tank or chamber 3 is a part of a tank 4, in which tank there is also a lubricating oil chamber 5, 50 and an air chamber 6. The division walls between the chambers 3, 5 and 6 are indicated by the dotted lines 5' and 6'. This

air chamber 6 and a lubricating oil chamber are not essential to the present invention, and do not form any part thereof.

55

A suitable air pump 7 is operatively connected in any desired manner with the motor (not here shown). Only a portion of the air pump cylinder is here illustrated, and its connection with the engine is also not 60 illustrated, for the reason that they are not essential to a full understanding of the present improvement. Any desired form of air pump may be used, and this air pump is connected with the upper portion of the 65 main supply tank 1 through the medium of a pipe 8, and supplies a pressure of air to the top of the tank, and a constant pressure upon the gasoline contained therein. Preferably, a pressure-reducing valve 9 of any 70 suitable construction, is located in the communication 8 between the pump and the reservoir 1 for the purpose of maintaining substantially a uniform pressure in the tank 1. The air pressure in this tank 1 75 forces the gasoline through a pipe 10 which has its lower end communicating with the bottom of the tank to the auxiliary tank 3 with which the upper end of the pipe communicates. I preferably place a small chamber 11 between the pipe 10 and the auxiliary tank 3, and this chamber is provided with a suitable valve 12 through which gasoline 80 may be drawn for any desired purpose. This chamber 11 communicates with a passage-way 14 made in a casting 15 which is connected to the top of the auxiliary tank 3, and this passage 14 communicates with the tank 3 through an opening 20. Located in an enlarged portion 17 of the said passage, 85 is a suitable valve stem 18 carrying a valve 19 adapted to close the opening 20. This valve and its stem are operated in relation to the opening 20 through the medium of an intermediately-pivoted lever 21 which is 90 actuated by a float 22 movable vertically upon a guide or rod 23. Pressure having been created in the main tank 1, gasoline is forced through the pipe 10 to the passage-way 14, and when it reaches a predetermined level in the auxiliary tank 3, the valve 19 will close the opening 20 and cut off 95 the supply of gasoline to the tank 3. In this way the gasoline is maintained at a pre-

determined level in the tank 3. Gasolene then flows by gravity from the tank 3 through a pipe 24 to a float chamber 2', and from the float chamber 2' through a passage 25, and from this passage 25 the gasolene passes through an opening 27 where it is mixed with the air in the carbureter 2 and passes from the carbureter through the pipes 54 to the cylinders of the engine. The flow 10 of the gasolene through the opening 27 is controlled by a suitable valve 29 which is locked in position by a lock-nut 30. If, for any reason, it should be desired to cut off the flow of gasolene independently of the 15 automatically-acting float in the chamber 2', it can be accomplished through a valve 31 having an operating wheel 33 located at the inner side of the dash-board 32 of the vehicle.

20 Located at the upper end of the chamber 11 is a screening member 57 consisting of one or more layers of fibrous material, through which the gasolene is forced before it enters the auxiliary chamber 3, thus preventing 25 the entrance of any foreign matter into the said chamber, and also preventing any foreign matter from interfering with the proper operation of the valve 19 in the closing of the opening 20.

25 The foregoing system of supplying a fuel to explosive engines of motor-driven vehicles, is found to have many advantages in practical operation. It enables the supply tank to be placed outside of the body of the 30 vehicle in a low down position, and without occupying any body space, and at the same time maintains a gravity flow of the gasolene with a predetermined head, which is essential to the proper operation of a carbureter, 35 and in addition, the float-controlled chamber located between the high-up tank and the gasolene outlet to the carbureter, automatically controls the flow of the gasolene, and also automatically cuts off the flow of 40 gasolene and prevents the draining of the intermediate tank, so that there is always a supply of gasolene in the intermediate tank for the starting up of the engine, after 45 which the pressure is created in the low-down tank to supply gasolene therefrom to the high-up tank. It is necessary to have the gasolene which is supplied to the float-controlled carbureter to be supplied thereto under a uniform head in order that the float-controlled carbureter may properly act, and it is also necessary that some automatic 50 means be provided between the high-up tank and the gasolene outlet to the carbureter, and this is provided in my improved system 55 through the medium of the float-controlled chamber 2' into which the gasolene flows from the high-up tank before it reaches the outlet 27 to the carbureter. It is also found necessary for proper operation that the air 60 pressure in the low-down tank must not 65

exceed the closing force of the float 22, for otherwise the valve 19 would be forced open against the closing effect of the float 22 and cause the gasolene to be forced in a continuous stream through the tank 3 and through the float-controlled chamber 2'. This may be accomplished in several ways, but the preferred way is by means of the pressure-regulating device 9.

Having thus described my invention, what I claim and desire to secure by Letters Patent, is:-

1. A fuel supply system for automobile engines, comprising a low-down supply tank, an auxiliary tank in a plane thereabove, an air-pump operated by the engine and having communication with the low-down tank to supply air pressure thereto, a carbureter in a plane between the low-down tank and the auxiliary tank, a fluid communication between the low-down tank and the auxiliary tank, a positively operating cut-off in said communication and maintaining a fluid level in the auxiliary tank, a communication between the auxiliary tank and the carbureter, said communication having means for maintaining a fluid level in respect to the carbureter, whereby in an automobile the supply tank may be located low down and outside of the body of the car for the convenience in filling, and the auxiliary tank located above the engine to have a supply of fluid fuel for the engine irrespective of grades and unvariable fluid head on the carbureter irrespective of the level of the fluid in the supply chamber and the grade of the roads, all combined substantially as described.

2. A fuel system for automobile engines, comprising a fluid supply tank located outside of the body of the vehicle; a high-up auxiliary tank having a fluid communication with the low-down tank, a carbureter located in a plane between the two tanks, a float controlled chamber located between the high-up tank and the carbureter to maintain a predetermined level of fluid in respect to the carbureter, a positively acting cut-off in the communication between the high-up tank and the low-down tank to maintain a predetermined level of fluid in the high-up tank, and an air pump operated by the engine and connected to the low-down tank to supply air-pressure to force the fluid from the low-down to the high-up tank, substantially as and for the purpose set forth.

3. A fuel supply system for automobile engines, comprising a carbureter, a low-down supply tank in a plane below the carbureter, an auxiliary tank in a plane above the carbureter, an air pump connected with and operated by the engine, a communication between the air pump and said low-down tank, an air pressure regulator in the communication controlling the pressure in

the low down tank, means positively and automatically cutting off the flow from the low down tank to the auxiliary tank at a predetermined period in the filling of the latter tank, a gravity feed communication between the auxiliary tank and the gasolene outlet of the carbureter, and a float-controlled chamber in said gravity feed commu-

nication at a point between the auxiliary tank and the carbureter. 10

In testimony whereof I affix my signature in presence of two witnesses.

ALEXANDER WINTON.
